UNITED STATES PATENT OFFICE.

JOHN FRANCIS OTIS, OF OSWEGO, NEW YORK.

STEAM GENERATOR.

Application filed June 28, 1920, Serial No. 392,402. Renewed February 21, 1927.

This invention relates to certain improvements in steam generators; and the objects and nature of the invention will be readily understood by those skilled in the art in the light of the following explanation of the accompanying drawings illustrating what I now believe to be the preferred embodiment of the invention from among other forms, constructions and arrangements within the spirit and scope thereof.

The steam generator of this invention is particularly intended for use where a comparatively small compact structure is required to operate under high temperature to evaporate a comparatively large volume of water per unit of time. Generators of this type usually embody a steel shell and a comparatively large number of small diameter copper fire tubes. Often such generators are under six feet in vertical length (including the fire box) with tube sheets under five feet in diameter and carrying over a thousand approximately half inch copper fire tubes approximately less than three feet in length and, are required to evaporate approximately two hundred and fifty gallons of water per hour.

Burning or injury of the lower end portions of the fire tubes and cutting or loosening of the fire tubes in the tube sheets, have constituted serious difficulties in the operation of boilers of this type, and these troubles have been due to excessive evaporation at the top surface of the bottom tube sheet under the intense heat of the oil burner flame and to the employment of the great mass of copper fire tubes in connection with a generator shell composed of metal other than copper, usually of steel.

It is the object of my invention to provide exceedingly simple, durable, economical and effective means for reducing these difficulties to the minimum by providing a fire-tube-protecting supply of water on the lower tube sheet and by rendering the shell longitudinally expansible and contractile approximately with the fire tubes, all by means of a peculiar shell formation.

With these and other ends in view, my invention consists in certain novel features in construction, and in combinations and

arrangements as more fully and particularly set forth and specified hereinafter.

Referring to the accompanying drawings:

The single figure shows a steam generator, embodying my invention, in longitudinal section.

In the drawings, I show a generator of the type hereinbefore mentioned and embodying an upright approximately cylindrical boiler shell 1; top tube sheet 2; bottom tube sheet 3; the mass of vertical fire tubes 7 at their lower ends opening into a combustion chamber surrounded by the water leg 5 and at their upper ends openings into a combustion chamber under hood 8. The generator is mounted on a suitable base providing a burner chamber 9 lined with fire brick or refractory material.

The water supply for the generator enters the lower end portion of the water leg 5 through feed water pipe a.

The steam after passing through any suitable separator plate 13 within the steam space of the boiler, leaves the boiler through steam pipe 10, superheater 11, and offtake pipe 12, or by any other suitable means or in any desirable manner.

In the embodiment illustrated, the top tube sheet 2 is flat and greater in diameter than the steam space of the boiler and is welded, riveted or otherwise secured at 21 on the out turned or flanged top end of the shell. The upper end of the shell is enlarged or flared outwardly on curved lines and terminates in the annular external horizontal flange 20 on which the top tube sheet is secured to form a tight joint. The arrangement of this tube sheet and the shell at this point, and the shell flare, provide for longitudinal expansion of the shell with respect to the portion of the tube sheet receiving the tubes, or in other words, an expansion joint or longitudinally expansible connection is established between the cylindrical portion of the shell below said flare and the tube-receiving portion of said sheet.

The bottom tube sheet is bent to form depending annular wall 4 cooperating with the lower end portion of the shell 1 to form water leg 5, of substantial capacity and the

lower end of wall 4 is flanged at 6 and welded or riveted to the shell to form a tight joint and to close the bottom of the water leg; and also to form a longitudinally expandible connection between the shell and bottom tube sheet, particularly with respect to the portions of the tube sheets that receive the tubes. In the embodiment illustrated, the boiler shell is formed without intermediate annular joints. The shell may be formed by rolling or otherwise manipulating or bending a single sheet to produce the shapes desired, or if the shell is made up of several sheets riveted or welded together (in this embodiment). I do not show distinct upper and lower sections united by an annular intermediate expansion joint, although I do not wish to limit all features of my invention to the one-piece shell as thus defined. The one-piece shell, as thus defined, is rolled or otherwise bent to form an intermediate longitudinally expandible portion which also constitutes a water deflector.

In the example illustrated, the diameter of the portion of the shell surrounding the water leg, exceeds the diameter of the cylindrical portion of the shell that surrounds the space occupied by the fire tubes, and the diameter of said upper portion exceeds that of the intermediate portion of the shell that forms said annular deflector and expandible portion. In the form shown by the accompanying drawings, said intermediate portion constitutes an annular inward contraction or bulge 25 on curved lines and approximately U-shaped in cross section. At the lower end of this contraction, the shell starts to contract inwardly and upwardly at the upper portion of the water leg and in a horizontal plane below the horizontal plane of the horizontal tube-receiving portion of the lower tube sheet. The upwardly inwardly curving lower wall or side 25^a of the contraction extends inwardly over the water leg and over and above the lower tube sheet and thereby contracts the upper end of the water leg and in connection with the top surface of said tube sheet forms an annular mouth 25^b for the water leg that opens or is directed approximately horizontally and inwardly toward the center of the water space on the top surface of said sheet. The contraction from thence curves upwardly and outwardly to form the top side or wall 25^c of the contraction which gradually merges upwardly on curved lines into the upper cylindrical wall of the shell. The inner surface 25^d of the floor or approximate vertical portion of this bulge 25 approximately approaches the outer fire tubes, i. e. approaches as close as possible to said tubes without contracting the same under all conditions of expansion and contraction. In other words, the bulge at its point 25^d of

smallest internal diameter, is located a comparatively short distance above the horizontal top surface of the lower tube sheet and is as close as possible to the outer fire tubes without actually contacting the same. This bulge formation provides the shell with an intermediate expandible portion, to aid in rendering the shell longitudinally elastic or expandible with respect to the tube-receiving portions of the tube sheets so that the shell can expand and contract with said tubes to reduce to the minimum danger of the joints between the tubes and sheets becoming loose or damaged by reason of unequal expansion and contraction between the tubes and shell.

This bulge also by reason of its relation with respect to the water leg and bottom sheet, sets up and maintains an inward flow of water on the top surface of said tube sheet to protect the lower end portions of the tubes, particularly the inner or central tubes. The boiler water supply enters the water leg and consequently there is a constant flow of water from said leg, and the mouth of the leg is so formed by the bulge as to hold the water down on said tube sheet and direct the same inwardly in the mass of tubes. This action is aided by the close approach of the bulge to the tubes, particularly as the top side or wall of the bulge also directs the water flowing down at the inner surface of the upper part of the shell, inwardly into the mass of tubes.

It is evident that various changes, modifications and variations might be resorted to without departing from the spirit and scope of my invention and hence I do not wish to limit myself to the exact disclosures hereof.

What I claim is:—

1. A steam generator having a water leg provided with the feed water inlet, and embodying upper and lower tube sheets, fire tubes joining said sheets, and an enclosing single-section shell joining said tube sheets, said shell formed with an intermediate inward annular bulge closely approaching the tubes without contacting the same and extending inwardly over the water leg and over and approaching the bottom flue sheet to cooperate therewith forming the water leg with an annular contracted top mouth opening inwardly above the bottom sheet to maintain a flow of water from the leg inwardly on the flue sheet, the upper side of said bulge arranged to direct water flowing down above the bulge inwardly among the tubes, said bulge forming the shell with an intermediate longitudinally expandible portion.

2. A steam generator having an annular depending water leg, comprising upper and lower tube sheets, a mass of fire tubes joining said sheets and constituting the sole connection between said sheets within the gen-

erator, and an outside shell, said shell formed with a curved intermediate annular inward bulge or contraction overhanging the bottom sheet and the water leg and as closely surrounding the mass of tubes as possible without contacting the same and in conjunction with the bottom sheet forming a vertically contracted and inwardly extend-

ing discharge mouth from the water leg, the internal diameter of the sheet at said bulge being less than the internal diameters of the shell above and below said bulge, said bulge providing the shell with a longitudinally expansible portion. 10

JOHN FRANCIS OTIS.
